UNITED STATES PATENT OFFICE.

MATTHEW T. CHAPMAN, OF AURORA, ILLINOIS.

ROTARY PUMP.

1,307,115.

Specification of Letters Patent. Patented June 17, 1919.

Application filed April 19, 1915. Serial No. 22,361.

To all whom it may concern:

Be it known that I, MATTHEW T. CHAPMAN, a citizen of the United States, residing at Aurora, in the county of Kane, State of Illinois, have invented certain new and useful Improvements in Rotary Pumps, of which the following is a specification, reference being had to the accompanying drawings.

- 10 My invention relates to rotary pumps and it has for its principal object the provision of new and improved means for protecting the bearings of the pump shaft from the sand and grit pumped up with the water.
- 15 As is well recognized in the pump art, when the bearings of the rotary shaft are open to the water being pumped and no protecting means is provided for preventing the entrance of sand and grit into the bearings, the
- 20 bearings very soon become seriously worn and cut out so as to very materially decrease the efficiency of the pump. It is one of the specific objects of my invention to provide protecting means for the bearings of a pump
- 25 shaft involving means for forcing clean water under pressure from the bearings, thus preventing the entrance of the dirty water being pumped, this being accomplished without the use of such a shaft inclosing-casing
- 30 as is very often used for this purpose. It is another object of my invention to provide a new and improved form of bearing by the use of which I am enabled to accomplish my objects. It is another object of my invention
- 35 to improve devices of this type in sundry details hereinafter pointed out. The preferred means by which I have accomplished my objects are illustrated in the accompanying drawings and are hereinafter specifically
- 40 described. That which I believe to be new and desire to cover by this application is set forth in the claims.

In the drawings:

Figure 1 is a central vertical section 45 through the apparatus at the top of the well;

Fig. 2 is a horizontal cross-section taken substantially on line 2—2 of Fig. 1;

Fig. 3 is a central vertical section through the water-raising elements down in the well; 50 and

Fig. 4 is a central vertical section through a modified form of shaft bearing.

Referring to Figs. 1 to 3, in which corresponding parts are indicated by the same 55 reference characters,—

10 indicates the water discharge head

fixedly secured in position in any suitable manner at or near the top of the well. Secured to the water discharge head 10 and rising therefrom is a stationary frame 11, 60 upon a sleeve 12 at the upper end of which, is revolubly mounted a pulley 13, the lower end of which pulley extends down about the upper end of the frame 11. An anti-friction bearing 14 of any suitable type is interposed between the sleeve 12 and the hub of the pulley 13 adapted to receive the side thrust of the pulley upon the frame, and an anti-friction bearing 15 of any suitable type is interposed between the hub of the pulley 70 and the frame 11 adapted to support the weight and to receive the down thrust of the pulley 13 and its connected parts. The sleeve 12 is out of contact with the shaft 16 which is keyed in the hub of the pulley 13, 75 whereby the anti-friction bearings 14 and 15 are adapted to be the entire support of the pulley and the shaft upon the frame 11. An anti-friction thrust bearing 16^b is adjustably supported on the shaft 16 by means 80 of a collar 16^c held in position by a suitable set-screw, said thrust bearing being adapted to limit the upward movement of the shaft relative to the frame 11. A flange 17 is secured to the upper end of the frame 11 about 85 the anti-friction bearings 14—15, providing a receptacle for a suitable lubricant for said bearings, a gage 18 of any suitable type being connected with said receptacle for showing the height at which the oil stands there- 90 in. Lock-nuts 19 are mounted by means of screw-threads upon the upper end of the shaft 16 above the hub of the pulley 13 adapted to hold the shaft 16 adjustably in position relative to the pulley and to the 95 frame 11, as will be readily understood.

Depending from the water discharge head 10 is a pump casing or water discharge casing 20 composed of a plurality of sections suitably joined together, as hereinafter described. The uppermost pump casing section 20 is secured to the water discharge head 10 by means of a ring 21 secured by means of screw-threads upon the upper end of the section 20, said ring being secured to the head 100 10 by means of a plurality of bolts 22. Connected to the head 10 by means of screw-threads and extending to one side therefrom is a water discharge pipe 23. A packing 24 of any suitable type is held by an adjustable gland 25 in position in the upper wall of the water discharge head 10 about the shaft 16. 110

The lower end of the lowermost section of the pump casing 20 is connected by means of a collar 26 and bolts 27 to the upper end of a runner head 28. A bearing sleeve 29 for the shaft 16 is carried by the head 28, being held in central position therein by means of ribs 30. Secured in any suitable manner below the runner head 28 are a series of runner casings 31 in which runners 32 feathered upon the shaft 16 are adapted to rotate. The runners are spaced apart from each other by means of sleeves 33, and the lowermost runner 32 is adjustably held in position upon the shaft 16 by means of 10 lock-nuts 34—35 secured by means of screw-threads upon the said shaft. Connected to the lowermost runner casing 31 by means of bolts 36 is a bearing head 37, supporting, by means of ribs 38, a bearing sleeve 39 in central position relative to the head 37. A collar 40 embracing the upper end of the bearing sleeve 39 is feathered upon the shaft 16 above the bearing sleeve 39, being held yieldingly in position by a spring 41 bearing 20 at its upper end against a collar 41^b fixed on the shaft. A suction pipe 42 is secured by means of a collar 43 and bolts 44 upon the lower end of the bearing head 37, the suction pipe 42 being adapted to extend down into 30 the well to the limit of the suction power of the runners 32 so as to prevent the pump from sucking air as the level of the water is lowered in the well by the action of the pump.

I have provided means similar in a general way to that shown in my application, Serial No. 16,101, filed March 22, 1915, for forcing a limited amount of water downward for lubricating and washing out the 40 bearings of the pump shaft. This means comprises a runner 45 slidably mounted upon the shaft 16 adjacent to the upper wall of a runner casing 46 which is suitably supported from the water discharge head 10. Suitable packings 47—48 are secured about the shaft 16 above and below the runner 45, respectively, and two nuts 45^b serve to limit the upward movement of the runner relative to the shaft. A feed pipe 49 is connected to 50 the upper end of the runner casing 46 above the runner 45, from which it extends into suitable position near the bottom of a water tank 50, being provided with a strainer 51 of any suitable type at its lower end. Another pipe 52 opens out of the pipe 49 being provided with a stop-cock 53 intermediate its ends and having a funnel 54 mounted upon its upper end. A discharge pipe 55 is connected with the casing 46 below the runner 45, a screen or strainer 56 of any suitable type being interposed between the runner 45 and the upper end of the pipe 55. By a suitable adjustment of the nuts 45^b, the runner 45 may be adjusted vertically upon the 60 shaft to bring it into proper position rela-

tive to the casing 46 without disturbing the adjustment of the lower runners 32.

The lower end of the pipe 55 communicates with an annular opening 57 formed in the inner face of the bearing sleeve 29 near the upper end of the said sleeve. From the annular chamber 57 the water which is forced downward through the pipe 55 by the runner 45, as hereinafter described, passes through a suitable hole 58 extending 70 through the lower end of the shaft 16, or through a pipe 59 to an annular recess 60 formed in the inner face of the lower bearing sleeve 39. From the annular recess 60 the water passes upward along suitable 75 spiral grooves 61 formed in the outer face of the shaft 16 for lubricating and washing out the said bearing as is set forth in my prior application above referred to, the water being adapted to escape from the annular recess 62 between the collar 40 and the sleeve 39 by seeping through the bearing between the collar 40 and the sleeve 39, the collar 40 being adapted to yield against the action of the spring 41. The water from 80 the annular recess 57 also passes downward along the spiral grooves 63 for lubricating and washing out the bearing of the shaft in the sleeve 29, the water thus passing down the shaft being adapted to escape through the ducts 64 extending diagonally downward through the hub of the uppermost runner 32. A ring 65 is loosely mounted in an annular 85 groove 65^b in the lower end of the bearing sleeve 29, said ring being adapted to rest 90 upon the uppermost runner 32.

A packing 66 is mounted in the upper end of the sleeve 29 about the shaft 16, a spring 67 bearing at its upper end against a collar 68 adjustably mounted upon the shaft 16 105 being utilized for holding the gland 69 yieldingly in position, a collar 67^b feathered on the shaft 16 being interposed between the spring 67 and the gland for taking the wear.

The adjacent sections of the water discharge pipe 20 are connected together by means of collars 70—71 which are mounted by means of screw-threads upon the ends of said sections, said collars being secured together by means of bolts 72. The inner 110 faces of the collars 70—71 are rabbed out to provide an annular space for the reception of a collar 73 which is connected by means of radially-extending ribs 74 with a bearing sleeve 75, in the construction shown, the collar 73, ribs 74 and sleeve 75 being formed integrally with each other. The inner face of the bearing sleeve 75 is provided with an annular recess 76 which is connected with the pipe 55 by means of a 115 short laterally-extending pipe 77. Packings 78 and 79 are mounted in the ends of the sleeve 75 on opposite sides of the annular recess 76.

When it is desired to start the pump in op- 120

130

eration, the valve 53 is opened and a supply of water is poured into the pipe 49 through the funnel 54, a foot-valve of any suitable type in the pipe 49 preventing such water from escaping into the tank 50. The water enters the casing 46 and passes thence through the pipe 55 to the several bearings 75 in the line of shafting, serving to lubricate such bearings. A part of the water also passes down to the bearing sleeves 29 and 39 for lubricating those bearings. After the bearings of the shaft have been suitably moistened, the valve 53 is closed and power is applied to the pulley 13 by a belt or in any other suitable manner for rotating the shaft 16 and the several runners mounted upon the shaft. The runner 45 operates in precisely the manner described in connection with my former application above referred to, causing water to enter the casing 46 through the pipe 49, which water is forced outward along the upper wall of the casing 46. This runner is smooth on its under side to avoid centrifugal action. The pressure on the upper side of said runner or impeller increases from the hub to the rim, caused by the rotation of the centrifugal vanes fixed on the upper side thereof, while the pressure on the smooth under side is uniform and equal to that at the rim of the runner or impeller. An unbalanced upward pressure is thereby created. By reason of the restricted opening from the casing 46, and by reason of the fact that the amount of water forced downward by the runner 45 is very much less than the amount of water normally adapted to be pumped by a runner of this size rotated at a similar speed, a very considerable pressure is exerted in the casing 46 upon the under face of the runner 45, serving to relieve from the thrust bearing 15 a very great proportion of the weight of the shaft and of the column of water raised by the runners on the shaft. In case the upward pressure upon the shaft is sufficient to lift the shaft, the anti-friction bearing 16^b serves to limit the upward movement so as to prevent the runners 45 and 32 from being moved into frictional engagement with the runner casings. The water which finds its way through the pipe 55 to the annular recesses 76 of the bearings 75 serves not only to lubricate the bearings but also to flush out the bearings and to prevent the water being forced upward past the bearing in the water discharge casing from entering between the shaft and the sleeve. In the same way the water delivered from the pipe 55 to the annular recesses 57 and 60 serves to wash out the bearings of the shaft in the sleeves 29 and 39 respectively, the water being forced in each instance toward the water raising elements to prevent the entrance of the dirty water being pumped, the grooves 63 and 61 being cut in such a direction that the water in such

grooves is forced by the screw action of the grooves toward the runners 32.

In Fig. 4, which shows a modified form of bearing for the shaft, the parts which correspond to the parts of the structure hereinabove described are indicated by the same reference characters, but with the addition of an exponent "a". In this figure, the bearing sleeve 80 is used provided with an annular recess 81 to which the pipe 77^a is connected for conducting water thereto from the pipe 55^a. The ends of the sleeve 80 are at right angles relative to its length so as to have a square bearing engagement with collars 82-83 feathered upon the shaft 16^a adjacent thereto. Springs 84-85 are interposed between the collars 82-83 and collars 86-87, respectively, which are adjustably secured in position upon the shaft 16^a. The spring-pressed collars 82-83 serve as metal packing members, the springs 84 and 85 being adapted to be tightened as desired for obtaining the requisite pressure upon the sleeve 80 for preventing the entrance of water between the collars 82-83 and the ends of the sleeve 80 against the pressure of the water being forced outward from the annular recess 81.

So far as I am aware, I am the first in the art to provide means for delivering clean water to the interior of the bearings spaced along a line of pump shaft above the runners without the use of an inclosing shaft casing, and I therefore wish to claim this feature broadly, both in connection with the particular means I have shown in the drawings for delivering the water to the bearings and in connection with any other suitable means for this purpose. It will be understood, moreover, that the structure may be varied in many details without departing from the spirit of my invention, and my claims are to be construed accordingly.

While I have described the bearings as being lubricated by water and prefer to use such a lubricant when the pump is being used for pumping water, it will be understood that I do not wish to restrict myself to the use of any particular lubricating element as distinguished from some other suitable lubricant. It will be appreciated that any means for forcing water through a bearing would serve equally well without change to force any other suitable lubricant through the bearing. The claims, therefore, in calling for means for forcing one type of lubricant through the bearings are broad enough to cover the same or similar means for forcing another suitable lubricant through the bearings.

What I claim as my invention and desire to secure by Letters Patent, is—

1. In a rotary pump, the combination of a sectional water discharge casing, a rotary pump shaft extending downward therein, a

- collar at each joint in the water discharge casing secured between the adjacent ends of the casing sections, a plurality of bearing sleeves for said shaft integrally connected 5 with said collars respectively, and means for delivering clean water into each of said bearing sleeves for preventing any foreign substance carried by the water being pumped from entering.
- 10 2. In a rotary pump, the combination of a sectional water discharge casing comprising two casing sections, connecting sleeves secured by means of screw-threads upon the adjacent ends of said sections respectively, 15 and bolts securing said two connecting sleeves together, a collar positioned between said two connecting collars and between the ends of the said sections secured tightly in position by said bolts, a bearing sleeve 20 formed integrally with said last-named collar, a shaft extending downward in said water discharge casing and through said bearing sleeve, said sleeve being provided with a recess on its inner face about said shaft, and means for delivering water under 25 pressure to said recess for preventing any foreign substance carried by the water being pumped from entering said bearing.
3. In a rotary pump, the combination of 30 a rotary pump shaft extending down into a well, a runner connected with said shaft, a water discharge casing through which the water pumped is adapted to rise in contact with the shaft along the major portion of 35 its length, bearings for said shaft within said water discharge casing, a pipe extending down alongside of said shaft and communicating with the interior of the several bearings, means for forcing a lubricant 40 through said pipe into said bearings adapted to prevent any foreign substance carried by the water being pumped from entering said bearings, and means serving to free of sand and grit the lubricant forced into said 45 pipe.
4. In a rotary pump, the combination of 50 a rotary pump shaft extending down into a well, a runner connected with said shaft, a water discharge casing through which the 55 water pumped is adapted to rise in contact with the shaft along the major portion of its length, bearings for said shaft within said water discharge casing, a pipe extending downward alongside of said shaft and 60 communicating with the interior of the several bearings, and a runner mounted on said shaft near its upper end adapted to force a lubricant through said pipe into said bearings for preventing any foreign substance carried by the water being pumped from en- tering said bearings, the outlet from said runner being comparatively small relative to the capacity of the runner whereby the runner exerts an upward pressure for supporting a part of the weight of the shaft 65 and its connected parts.
5. In a rotary pump, the combination of 70 a water discharge head, a sectional water discharge casing connected therewith and depending therefrom, a rotary pump shaft extending downward through said water discharge head and said water discharge casing, a shaft bearing supported opposite a joint between adjacent sections of the water discharge casing with which bearing 75 the water pumped is brought into contact as it rises through said water discharge casing, a runner casing supported by said water discharge head about said shaft, a runner mounted on said shaft within said runner casing, a pipe connecting said runner casing below said runner with the interior of said bearing whereby the runner is adapted to force a lubricant into said bearing for preventing any foreign substance carried by the water being pumped from entering said bearing, and means serving to 80 free from sand and grit the lubricant forced into said pipe.
6. In a rotary pump, the combination of 85 a vertical driving shaft, pumping means mounted thereon down in the well, and auxiliary pumping means slidably and adjustably mounted upon the driving shaft for forcing a lubricant to the bearing or bear- 90 ings of said shaft adapted to create a pressure underneath the said auxiliary pumping means and to lift up on said shaft for reducing the friction of the shaft supporting 95 bearings thereby reducing the power re- 100 quired for operating the pump.
7. In a vertical deep well pump of the type described designed to pump sand or other foreign substances with the water, the combination of a bearing or bearings located 105 upon the drive shaft in the water passage of the pump in contact with the water rising therethrough, and means for preventing sand from entering the bearing, comprising a cap having a working sliding fit upon the 110 shaft and revoluble therewith and bearing against the end of the bearing and held in contact therewith by yielding means, and means for producing a continuous discharge 115 of lubricant from the bearing to prevent gritty substances carried by the water being pumped from entering the bearing and injuring the bearing or the shaft.

MATTHEW T. CHAPMAN.
